UNITED STATES PATENT OFFICE.

EDWARD G. BUDD, OF PHILADELPHIA, PENNSYLVANIA, ASSIGNOR TO THE EDWARD G. BUDD MANUFACTURING COMPANY, OF PHILADELPHIA, PENNSYLVANIA, A CORPORATION OF PENNSYLVANIA.

METALLIC DOOR FOR AUTOMOBILES.

1,264,266.

Specification of Letters Patent. Patented Apr. 30, 1918.

Application filed January 8, 1915. Serial No. 1,230.

To all whom it may concern:

Be it known that I, EDWARD G. BUDD, a citizen of the United States, residing at Philadelphia, county of Philadelphia, State 5 of Pennsylvania, have made a certain new and useful Invention in Metallic Doors for Automobiles, of which the following is a specification.

This invention relates to metallic doors 10 for automobile bodies.

The object of the invention is to provide a metallic door for automobile bodies which is simple in structure, economical to manufacture, and strong, durable and efficient in 15 operation.

A further object is to provide a door structure wherein the parts are sheet metal stampings of simple form easily and economically produced, and capable of being readily and quickly assembled. 20

Other objects of the invention will appear more fully hereinafter.

The invention consists substantially in the construction, combination, location and relative arrangement of parts, all as will be 25 more fully hereinafter set forth, as shown in the accompanying drawing, and finally pointed out in the appended claim.

Referring to the accompanying drawing:—

Figure 1 is a view in elevation of the outer face of a metallic door constructed in accordance with my invention, a portion being broken out and in section to show the 35 pocket or receptacle in the door.

Fig. 2 is a vertical section of the same on the line 2, 2, Fig. 1, looking in the direction of the arrows.

Fig. 3 is a broken view in horizontal section on the line 3, 3, Fig. 1, looking in the direction of the arrows.

Fig. 4 is a view similar to Fig. 3, on the line 4, 4, Fig. 1, looking in the direction of the arrows.

The same part is designated by the same reference numeral wherever it occurs throughout the several views.

In the manufacture of doors for automobile bodies or other vehicles, and especially 50 where such articles are made up in large quantities, it is a matter of material consequence to provide a structure composed of few parts which are simple in form, capable of being readily and easily made from

stampings of sheet metal and assembled and secured together quickly and efficiently, thereby securing economy in the manufacture thereof. It is also important to secure sufficient strength to enable it to withstand the hard usage to which such articles are subjected. 60

It is among the special purposes of my present invention to produce a metallic door which secures in the manufacture thereof and in the finished product, the advantages 65 and objects above set forth.

In general, a door constructed in accordance with my invention comprises an inner and an outer panel stamped out from sheet metal and into suitable form and contour, 70 and suitably assembled and secured together.

The outer panel 5 is a stamping of suitable contour vertically and horizontally to conform symmetrically to the lines of the 75 automobile or vehicle body. This panel if desired, may be pressed out along its border, as indicated at 6 to form an outwardly offset bead raised which is not only ornamental but which also stiffens and strengthens 80 the door structure when completed. This bead however, may be dispensed with, if desired. The extreme edge of the outer panel 5 is formed with a lip 7, along the vertical and bottom portions of the panel, 85 and this lip is turned inwardly and backwardly upon the body of the adjacent portion of the panel. The inner panel 8, is also made from a metal stamping, and is formed on its inner face adjacent the edges 90 thereof with a depressed channel 9 which not only secures stiffness of the panel, and of the door structure, when assembled, but also affords means for seating suitable strips 95 through which the upholstering or interior finish or trim is applied to the panel. Beyond the channel 9 at the hinge side and bottom edges of the door, the metal sheet or panel 8, is bent outwardly at substantially right angles to the plane of the body 100 of said panel, as shown at 10, Figs. 2 and 3, and at its extreme edge is bent laterally with respect to the portion 10, to form a flange 11, over which flange the lip 7 engages, these parts being suitably secured together, preferably by welding them. Along the vertical free edge of the door the inner panel 8 is bent outwardly and this out-

105

wardly bent portion or flange 15 is pressed into shape to form a stop shoulder 12; see Fig. 4, to coöperate with and seat against the side door jamb 13 of the automobile or 5 vehicle body, the shoulder 12 being faced with the usual rubber, felt or other suitable cushion strip 14. At its extreme edge this flange 15 is bent to form a lateral flange 16, over which engages the lip 7 of 10 panel 5, the parts being welded or otherwise secured together. If desired, and in order to still further relieve the door of shock or jar when slammed shut, a rubber or other resilient member 18, may be applied 15 in any convenient manner to the outer side of the shoulder 12.

In order to form the usual pocket or receptacle in the door, the space between the inner and outer panels is utilized, the inner 20 panel being pressed out centrally, as indicated at 20, to form a pan 21. The side portions 23 of the pan member 21 afford a support for the hinge members 24 of the door. These hinge members pass transversely 25 through the flange 10 of the inner panel 8 and into the space between the inner and outer panels, and are secured to the side flange portions 23 of the pan 21, as clearly shown. The lip 7 at the lower edge of the 30 door forms a shoulder stop to coöperate with the member 25 of the door sill.

Interposed between the inner and outer panels at the upper edge of the door is a horizontally extending member 26 which is 35 pressed or otherwise formed into channel shape, the channel being presented up-

wardly. This member may be formed by suitably bending and shaping the upper edge of one of the panels, or it may be a separate piece. This member not only serves to brace 40 and strengthen the door at its upper edge but it also affords a seat for a wooden or other strip 27 to which the upholstery and the finishing strip 28 may be attached.

While I have shown and described a specific structure of door embodying my invention it is to be understood that many changes and variations in detail might readily occur to persons skilled in the art and still fall within the spirit and scope of my invention, but having now set forth the objects and nature of the invention and a structure embodying the principles thereof, what I claim as new and useful and of my own invention, and desire to secure by patent is,—

A door for automobile bodies composed of an inner and an outer sheet metal panel, said panels secured together in offset relation to each other, the inner panel being centrally depressed to form a pocket pan, and hinge 60 members extending into the space between said panels and secured to the wall of the pocket pan.

In testimony whereof I have hereunto set my hand in the presence of the subscribing 65 witnesses, on this 9th day of December A. D. 1914.

EDWARD G. BUDD.
